CENTRIFUGAL EXTRACTING AND DIS-
CHARGING MECHANISM

Edward L. Miller, Green Island, N. Y., assignor,
by means assignments, to American Machine
and Metals, Inc., New York, N. Y., a corpora-
tion of Delaware

Application April 21, 1933, Serial No. 667,157

13 Claims. (Cl. 210—73)

The invention relates to new and useful improvements in mechanisms for centrifugally extracting and automatically disposing of the residual solids; and more especially to such new and useful mechanisms, wherein after extraction the solids are automatically dumped from the basket.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a central, vertical section through an extractor mechanism embodying the invention;

Fig. 2 is a full top plan of the mechanism of Fig. 1 with the top closure closed;

Fig. 3 is an enlarged vertical section taken substantially on the line 3—3 of Fig. 2;

Fig. 4 is a central, vertical section of the extractor, with the mechanisms for lifting the closure and the inner basket in elevation;

Fig. 5 corresponds to Fig. 4, but shows the closure removed and the inner basket lifted out of the outer basket;

Fig. 6 is an enlarged vertical section on the line 6—6 of Fig. 5;

Fig. 7 is a top plan, partly diagrammatic, of a series of extractors and a trolley conveyor for carrying the inner baskets to discharge;

Fig. 8 is an elevation of an extractor showing the cooperating safety devices for the inner and outer closures;

Fig. 9 is an enlarged partial vertical section of the modified form of locking means for the top closure for the inner basket; and

Fig. 10 is a top plan, partly broken away and partly in section, corresponding to Fig. 9.

One of the main objects of the invention is to extract from solution or suspension, and to discharge sticky solids, of which sewage sludge is an example, that cannot be handled commercially in a bottom discharge machine nor by the usual dumping basket mechanisms. A further object of the invention is to effect extraction and

discharge of sticky solids, and like difficult materials, rapidly and easily in the large quantities required by commercial conditions, such as exist for example in sewage disposal plants. Means are accordingly provided for effecting the extraction and discharge of such materials in large quantities, under commercial conditions and requirements, for taking care of the resultant heavy strains and great upward thrusts developed, and for effecting quick and easy and practically automatic dumping of the sticky materials from the basket; the preferred means also providing dumping and conveying devices serving a battery or plurality of the extractor units.

With these objects in view, mechanisms are provided by my invention including a removable basket having an unobstructed upper lip or discharge edge to facilitate dumping of sticky materials, and having a top ring for taking the upward thrust during extraction, the top ring being removable prior to, and replaceable after dumping, together with devices for securely maintaining the top ring against the relatively great upward thrust developed, the top ring preferably being also a complete closure for the removable basket.

Means are also provided by the invention for concurrently or sequentially lifting the basket from the structure and the top ring from the basket preparatory to dumping, for restoring the empty basket to the extractor and replacing the top ring on the basket by a continuous and automatic operation; the basket being mounted in connection with the lifting means so as to be automatically dumped by the unbalanced load, the empty basket being automatically restored to upright position preparatory to its replacement in the extractor.

The invention further provides safety devices which prevent closure of the curb lid until after the top closure for the removable basket has been locked in position, said safety means cooperating with the usual safety means which prevent starting of the machine until after the curb lid is closed.

Further objects of the invention, and the novel means by which they are attained, will be additionally set forth in the following description, it being understood that the preceding general statement and the following detailed description are exemplary and explanatory of the invention but not restrictive thereof.

Referring now in detail to the embodiment of the invention illustrated by way of example in the accompanying drawings, an extractor of the

open-top, link-suspension type is shown, having a casing or curb 1, flexibly carried on three link suspensions 2, whereby the curb is freely suspended from pillars or supports 3, fixed to and extending upwardly from the base plate 4. The curb or casing 1 is provided with a hinged closure 5. Within the curb 1 is rotatively mounted a basket 10, which may be called for convenience the permanent basket, having a perforated peripheral wall 11, and a bottom or floor 12 terminating centrally in a bearing hub 13. The hub 13 is rotatively supported on the beveled portion 14 of a shaft 15, which is journaled in a bearing 16, located centrally of and bolted to the floor 12 of the casing. Fixed to the lower end of shaft 15 is a combined brake drum and pulley 17, over which run driving belts 18, which likewise run over the driving pulley 19, driven by a motor 20, mounted in a support 21, carried by the curb 1 or casing 1.

In the illustrated preferred embodiment of the invention, there is provided (Figs. 1, 3, 4, and 5) an inner, removable and replaceable basket 31, having a downwardly decreasing conoidal perforate periphery 32, having an unobstructed top lip or edge to facilitate pouring off the solid or other residuum when the basket is dumped. The bottom 33 of basket 31 rests upon and is supported by the bottom 12 of the permanent basket, and centrally basket 31 has an upwardly decreasing conoidal part 37, encircling the bearing hub 13 of the permanent basket 10, and terminating in a top edge 38, upon which the top closure presses to hold the basket 31 firmly against the bottom of basket 10. Basket 31 is automatically centered within and spaced away from basket 10 by suitable means, such as the vertically disposed spacing pieces 34, fixed to, and projecting inwardly from, the inner wall of the permanent basket. Means are provided for holding the removable basket firmly in position within the permanent basket, said means being easily and quickly operated to release the inner basket for removal. As embodied a nut 42 is screw threaded on the top end of shaft 15 to press the top closure 45 against the top edge 38 of the basket, thereby clamping the bottom of the inner basket against the floor of the outer basket.

In connection with the removable basket, having no top flange, there is provided (Figs. 1 to 5) a top ring or cover, which is readily placed in position, is firmly locked for extracting, and is easily detachable to be lifted away preparatory to removing and dumping the basket. This device as embodied comprises a discoidal, complete top closure 45, adapted to rest upon the unobstructed top lip of the inner basket 31. Closure plate 45 is reinforced on the under side by annular angle irons 46 and 47. The plate 45 is centrally apertured, and the aperture is closed by an upwardly-extending cylindrical housing 48, having an outer horizontally-extending annular flange 49, fastened to the plate 45 by rivets. The housing 48 is centrally apertured and the threaded upper end of shaft 15 extends upwardly therethrough. The plate 45 about its central opening rests upon the upper edge 38 of the inner basket, and the hand nut 42 is screwed down in engagement with the top of the housing 48, and holds the closure 45 in position on the top of the inner wall of the basket, and also clamps the bottom of the inner basket 31 against the bottom of the permanent basket 10.

Means are provided for locking the periphery 5 of the top closure 45 to the peripheral wall of the

inner basket 31 at a plurality of points, in cooperation with devices for quickly and easily operating the locking means. As embodied (Figs. 1 to 5), a plurality of radially-disposed locking bars 57 are slidably mounted in guides 58, mounted on the top of closure plate 45. The outer ends of locking bars 57 are slideable into and out of openings in plates 59, which plates are fastened to and projecting upwardly from the peripheral wall 32 of the removable basket. The common operating means for simultaneously sliding all the locking bars 57 into and out of locking position comprise a disc 61, centrally apertured to fit rotatively about the cylindrical housing 48, and to rest upon the annular flange 49 of the housing. A hand wheel 62 is fixed to the upper part of the disc 61. The cam disc 61 is held in position by the bolts 50 which work in arcuate slots 63 in the cam disc to permit necessary angular movement of the cam disc. At the inner end of each locking bolt 57 is a pin 64, which projects into and works slidably in corresponding arcuate slot 65 formed in the under side of the cam disc 61. Thus by partial rotation of the hand wheel 62, all of the locking bars 57 are slid into the corresponding openings in the lugs 59 to lock closure 45, or are retracted therefrom to unlock the closure 45. To prevent movement of the wing nut 42 during basket rotation, and to prevent unlocking of the top closure, there is provided (Fig. 2) an annular, centrally-apertured plate 68, pivoted at 69 upon the top of the cam plate 61, the plate 68 having an arm or weight 71 projecting outwardly from the outside thereof, and having a tooth 70 projecting into its aperture.

Ratchet teeth 72 are formed on the hub of the nut 42, and when the extractor begins to rotate, the unbalanced weight 71 swings plate 68 about pivot 69, and tooth 70 engages with one of the teeth 72 and prevents circular motion of the wing nut with respect to the top closure.

Safety devices are provided for preventing closing of the curb closure unless the closure for the inner basket is locked. In the embodied form of said means, stop arms 79 are pivotally mounted at 80 upon the guides 58, a pinion gear 81 being formed on the end of each arm 79, the pinion meshing with a straight rack 82 formed in the top of the corresponding locking bar 57. When bars 57 are in locking position, arms 79 lie down and permit the curb lid 5 to be closed as shown in Fig. 3; but when the locking bars 57 are in retracted or unlocked position, arms 79 are in raised position, shown in Fig. 1, and prevent closure of the curb lid.

In accordance with certain features of the invention, means are provided operating concurrently or sequentially to remove the top closure from the inner basket, to lift the inner basket, dump it, return it to position and replace the top closure, preparatory to the next extracting operation. There is accordingly provided in connection with a removable basket, mechanism for removing and dumping the basket which automatically lifts the cover from the basket, carries it with the basket to the dumping station, and restores it on the basket as the basket is replaced. As embodied, it comprises a counterbalanced cover lifting device, the basket acting as an anchorage to first elevate the cover, the weight of the basket holding the cover up after both are lifted by the one device, and the removal of the weight of the basket by its replacement in the extractor permitting the cover to descend into position on the basket.

Said means as here embodied are adapted to cooperate with an overhead trolley conveyor device for carrying the baskets to and fro between the extractors and a dumping station. There is accordingly provided (Figs. 4, 5, and 6) a support 93, comprising two spaced-apart channel beams 92, with cross spacing members, and having a central suspension 94. Journalled in bearings 95 and 96 at either end of support 93 are sheaves 97 and 98. Over the sheaves, respectively, run cables 99 and 100. The inner ends of these cables are anchored to rods 101 fixed at either end in the side walls of saddles 102 and 103, respectively. Pairs of chains 104 and 105 are supported upon corresponding rods 106 and 107, fixed in the side walls of the upper part of the saddles, the chains at their lower ends being adapted to engage with corresponding pairs of hooks 108 and 109, fastened in diametral positions, to the top of the closure 45. Flexibly fastened to the outer ends of the cables 99 and 100, respectively, are corresponding plates 115 and 116, and projecting from these plates are corresponding headed pins 117 and 118. These are adapted to engage with and disengage from keyhole slots in supporting devices in diametral positions on the outer wall of the removable basket 31.

Cooperating means are provided in conjunction with said means for lifting and lowering the basket and removing and replacing the closure, comprising devices for maintaining the loaded basket upright, for releasing it to dump the unbalanced load, and causing the empty basket to automatically right itself. As here embodied, the basket has fixed thereto two diametrically opposite trunnions rotatively mounted, respectively, in two vertical hangers, there being a locking device at either side to hold the loaded and unbalanced basket upright between the supports. The trunnions in said embodiment are placed between the center of gravity of the loaded basket and the center of gravity of the unloaded basket, so that on disengaging the locking means, the basket will turn over, dump and right itself, when the locking means will again engage it.

The embodied form of these supporting devices (Figs. 3, 4, and 5) comprise each a vertical hanger 123, rotatably mounted on a hub or trunnion 124 formed on a plate 125 riveted to the outer wall of the basket. In the upper end of each of the hangers 123 is a keyhole slot 122, into which the headed pins 117 and 118 are inserted to constitute a rocking suspension for the basket. In the embodied locking devices for holding the basket upright on the hangers, there is fixed to the bottom part of each of the plates 125 a lug or detent 128, and a forked member 130 is pivotally mounted in a block 129, riveted to the bottom part of the corresponding hanger 123. The forked members 130 normally straddle the corresponding blocks 128 and prevent rotation, and after restoration of the basket, the forked member 130 may be again moved into locking engagement with the lug 128 to lock the basket in upright position.

The form of transporting means for the basket may be widely varied so far as concerns the main features of the invention, and as embodied, a hoisting track trolley, which may be of any known or suitable form is conventionally shown. This trolley 142 is shown running on a track 143, and may have an electrical hoist of known or other suitable form. The trolley hoist is shown with a chain 144 having a hook 145 which engages with the eye-bolt 94 of the basket and closure operating mechanism.

In operating the hereinbefore described mechanism, the curb lid 5 is opened, the nut 42 is unscrewed, and cam disc 61 is rotated to retract the locking bars 57. The trolley then hoists the member 93, and by reason of the greater weight of the basket holding the outer ends of the cables stationary, the top closure 45 is first raised from the basket-closing position of Fig. 4 to that of Fig. 5 without moving the basket. The top faces of the saddles 102 and 103 engage the bottom face of the carriage 93, as shown in Figs. 5 and 6, and stop further lifting of the closure 45. The hoisting being continued, the inner basket 31 is lifted from the permanent basket 11, as shown in Figs. 4 and 5. With basket 31 and its closure 45 in the position shown in Fig. 5, the trolley 142 is run along the track, and carries the basket to the point of discharge a. The forked detents 130 are rocked on their pivots and free the lugs 128, and due to the unbalanced load, the basket rotates on the hubs 124 and dumps the load. The empty basket then automatically rights itself, and the detents 130 lock the basket in upright position. The trolley is then run back and basket 31 is lowered into the permanent basket 11, and is centered by the members 34. The member 93 continues to descend, and basket 31 being at rest, the weight of the closure 45 and the accompanying movement of cables 99 and 100, and the closure is brought into closing position on the inner basket, the stops 200 and 201 on the cables 99 and 100 serve as limits to the travel of the cables and to line up the saddles 102 and 103 and the straps 115 when released from the closure 45. If the lowering of member 93 is stopped after basket 31 is restored, it can be loaded through the open top before the lid 45 is lowered to close the basket. After closure 45 is in position on the basket, the hand nut 42 and the locking bars 57 are operated to lock basket 31 in position as heretofore described.

The invention provides as one of its features interlocking safety devices for the inner basket closure and the curb closure to prevent starting the machine unless both closures are closed. In the embodied form this is effected by correlating a basket closure safety device, such as the arms 79 on the closure 45 for the basket 31 preventing closing the curb lid 5 unless the bolts 57 on the inner closure 45 are in locking position with a safety device controlling the motor to prevent starting unless the curb lid 5 is closed. The action of the safety arms 79 in connection with the curb lid has already been described. The motor controlling safety device cooperating with the curb lid 5 is shown in Fig. 8, and need not be described in detail. It is indicated generally by reference numeral 151, and in its operation prevents closure of the motor circuit unless the lid 5 is closed, and by means of member 152 engaging the pulley, it prevents the lid from being opened through the action of an interponent 153 with the arm 154 connected to the lid 5. A tension spring 155 encircling a telescoping rod 156 acts as a counterbalance for the lid 5. Cam operated closing clamps 157 serve to keep the lid tightly closed. After the motor is stopped, and the belt is not running, the member 152 permits the lever 158 to be swung to remove interponent 153 out of the way of the arm 154 to permit the curb lid to be raised. When the curb lid is in raised position, the locking bolts 57 of the basket 31 may be retracted, and the operation of lifting the inner closure and the inner removable basket and dumping it may be proceeded with. After the bolts 57

are locked, the arms 78 permit the curb lid to be closed, the handle 158 to be swung so as to reset member 152 and release stop button 160 which closes the motor circuit.

5. A modification of the mechanism for locking the inner top closure in position is shown in Figs. 9 and 10, wherein the locking of the closure at peripheral points and to the shaft are concurrently effected by a single actuating mechanism.

10 As embodied, a nut 167 is screwed onto the top end of shaft 15, the nut having an undercut portion 168 beneath the head 166. Slidably mounted in the cam disc 61 are a plurality of inwardly-extending, radially-disposed locking bars 169 which engage with the undercut portion 168 of nut 167. The inner ends of bars 169 are beveled so that when in locking position they pass into the undercut portion 168 of the nut 167 and thereby lock the central part of the lid 45 beneath the nut, they also cam or press it downwardly against the top edge 38 of the central top portion of the inner basket 31 and thereby press the bottom 33 of the inner basket 31 firmly against the bottom 12 of the outer basket 11.

15 20 25 The retracting means for the locking bars 169 comprise pins 172 working in cam slots 173 formed in the cam disc 61. Thus, when the hand wheel 62 is partially rotated the two sets of locking bolts 57 and 169 are concurrently locked or unlocked 30 and simultaneously lock and release the lid 45 at its periphery and its central opening, as well as clamping the inner basket 31 in position.

The invention in its broader aspects is not limited to the specific mechanisms shown and 35 described but departures may be made therefrom within the scope of the accompanying claims without departing from the principles of the invention and without sacrificing its chief advantages.

40 What I claim is:—

1. An extractor and discharging mechanism including in combination an extractor having a removable basket and a top closure therefor, means including a flexible running member which at 45 one end engages the basket and at the other end engages the closure for removing the closure from the basket and the basket from the extractor and sheaves mounted above said basket and cover and over which the flexible members are passed for lifting the basket and cover by the flexible members.

2. An extractor and discharging mechanism including in combination an extractor, a removable basket and a top closure therefor, and means 55 including a sheave and a cable running thereover, said cable being attached to the basket and to the closure, for removing the closure from the basket and the basket from the extractor.

3. An extractor and discharging mechanism 60 including in combination an extractor, a removable basket and a top closure therefor, suspension means upon which the basket is movably mounted for dumping, and lifting means including a sheave and a cable having its ends attached to the suspension means and to the top closure to lift the top closure from the basket and the basket from the extractor preparatory to dumping and for replacing the basket in the extractor and the closure on the basket.

70 4. An extractor and discharging mechanism 75 including in combination an extractor having a removable basket, a top closure therefor, a pair of suspension devices upon which the basket is rotatably mounted, and a vertically movable support, a pair of sheaves mounted thereon, cables

running over the sheaves, the ends of the cables being connected to the top closure and to the suspension devices.

5. An extractor and discharging mechanism including in combination an extractor having a removable basket, a top closure therefor, a pair of suspension devices upon which the basket is rotatably mounted, and a vertically movable support, a pair of sheaves mounted thereon, cables running over the sheaves, the ends of the cables being connected to the top closure and to the suspension devices and means for limiting the running of said cables.

6. An extractor and discharging mechanism including in combination a casing, a removable basket within the casing, a closure for the basket, a supporting member and means for raising and lowering it, and flexible running devices supported thereby and connected at either end to the basket and closure for lifting the basket from the casing and the closure from the basket and sheaves mounted above said basket and cover and over which the flexible members are passed for lifting the basket and cover by the flexible members.

7. An extractor and discharging mechanism including in combination a casing, a removable basket within the casing, a closure for the basket, a supporting member and means for raising and lowering it, and flexible running devices supported thereby and connected at either end to the basket and closure for lifting the basket from the casing and the closure from the basket and lowering the basket into the casing and the closure onto the basket when at rest within the casing and sheaves mounted above said basket and cover and over which the flexible members are passed for lifting the basket and cover by the flexible members.

8. An extractor and discharging mechanism including in combination a casing, a removable basket, a basket cover, basket lifting and cover removing means including a flexible running member connected at one end to the basket and at the other end to the cover, and a sheave over which said flexible member runs, means for lifting and lowering said sheave while the flexible member is freely running to remove the cover and lift the basket during the lifting movement and lowering the basket and replacing the cover during the lowering movement.

9. An extractor and discharging mechanism including in combination a casing, a cover for the casing, a removable basket, a basket cover, basket lifting and cover removing means including a flexible running member detachably connected at one end to the basket and detachably connected at the other end to the cover, and a sheave over which said flexible member runs, means for lifting and lowering said sheave while the flexible member is freely running to remove the cover and lift the basket during the lifting movement and lowering the basket and replacing the cover during the lowering movement.

10. An extractor and discharging mechanism including in combination a casing, a removable basket, a basket cover, a transverse support, a plurality of sheaves mounted on said support, flexible members running over said sheaves and connected at one end to the basket and at the other end to the basket cover, and means for lifting and lowering said support to lift the cover from the basket and the basket from the casing and to lower the basket into the casing and replacing the cover on the basket.

11. An extractor and discharging mechanism including in combination a basket, a basket cover separate from the basket, means for raising the cover and lifting the basket and lowering the basket and replacing the cover comprising a sheave, a cable running over the sheave and connectable at one end to the basket and at one end to the cover and means for lifting and lowering the sheave, and means for locking the cover in position on the basket when they are disconnected from said raising means. 5
12. An extractor and discharging mechanism including in combination a basket, two supporting members pivoted to the basket at opposite sides and below its center of gravity, latch members between said supports and the basket to pre- 10
13. An extractor and discharging mechanism including in combination a casing, a removable basket, a basket cover, cables connected at one end to the basket and at the other end to the cover, sheaves over which said cables run, a support for said sheaves, and a hoisting track trolley having a cable and means for connecting said cable to said support. 10

EDWARD L. MILLER. 15
